Donald L. Elliott, Los Angeles, Calif., assignor to
Allied Plastics Company, Los Angeles, Calif., a
partnership

Application April 16, 1945, Serial No. 119,003

Term of patent 14 years

(Cl. D86—10)

To all whom it may concern:

Be it known that I, Donald L. Elliott, a citizen
of the United States of America, residing in the
city of Los Angeles, in the county of Los Angeles,
State of California, have invented a new, origi-
nal, and ornamental Design for a Compact or
Similar Article, of which the following is a speci-
fication, reference being had to the accompany-
ing drawing, forming a part thereof.

Figure 1 is a top plan view of a compact or simi-
lar article, showing my new design, and Figure
2 is an edge elevational view thereof.

The essential features of the design reside in
the portions shown in full lines.

I claim:

The ornamental design for a compact or simi-
lar article, substantially as shown and described.

DONALD L. ELLIOTT.
